ROD LINE CONNECTER CONTROL

Irwin L. Dunn, Tulsa, Okla., assignor to Dunn & Lewis, a partnership composed of Irwin L. Dunn and James O. Lewis, Tulsa, Okla.

Application May 23, 1934, Serial No. 727,104

4 Claims. (Cl. 74—593)

My invention relates to a rod line of the type employed for connecting well pumping mechanism with a power unit, and more particularly employed for connecting a pump jack with a central power unit serving all of a group of wells.

In fields where production has fallen off to a point where it is uneconomical to pump each well with its individual power it is customary to connect a number of adjacent wells with a central power unit, and where the production is so low that continuous pumping is uneconomical or undesirable it is also customary to connect the well pumping mechanisms with the power for only sufficient periods during the day to effect removal of accumulated fluid from the well. Intermittent connection of the well pumping mechanisms with the power unit is ordinarily effected manually by means of hook-on and hook-off devices in the rod lines, but such practice requires an attendant for each hook-on and hook-off operation, and frequently results in injury to the attendant.

It is the object of my invention to effect saving of labor and avoid injury to workmen by hooking the lines on and off automatically, and to regulate the operating period of a well in response to timing mechanism so that the pumping period may be determined without necessity for the presence of an attendant.

In accomplishing these and other objects of the invention I have provided improved details of structure, the preferred form of which is illustrated in the accompanying drawing, wherein:

Fig. 1 is a perspective view of a series of rod lines, showing one line equipped with an automatic hook-off and another line with an automatic hook-on for disconnecting and connecting the pump ends with the power ends of the respective lines.

Fig. 2 is an enlarged detail, perspective view of a timing mechanism controlling the hook-on or hook-off of the lines, a part of the timing mechanism supporting post being broken away for better illustration.

Referring more in detail to the drawing:

1 designates a pump jack of conventional form adapted for reciprocating the sucker rods of a pumping well, and 2 a central power unit of conventional type adapted for operating line rods 3 connected with a plurality of jacks 1, in accordance with common practice. Certain of the rod lines 3 are made up of a pump end section 4 and a power end section 5 adapted for connection, while other lines 3 are made up of

similar sections 4'—5' adapted for disconnection, so that the wells served by the lines may be alternately pumped intermittently for periods determined by coupling and uncoupling of the respective rod sections.

For effecting the coupling and uncoupling, usually termed hook-on and hook-off, of the rod sections, 5 and 4' are each provided with a hook, which may be of any suitable type, as illustrated at 7 and 6 respectively (Fig. 1), and the rod sections 4 and 5' are respectively provided with loops 8 and 9 adapted for co-operation with the corresponding hooks 6 and 7 to operatively connect and disconnect the rod sections for alternate reciprocation by the power unit.

With this arrangement, when the hook-on sections are connected, the power unit pulls on certain line rods to lift the sucker rods and weight of the sucker rods returns the lines, the lines having the hook-off sections are idle and vice versa, the hook-on and hook-off of the lines being effected at the end of the outstroke of the rod, the attendant lifting the hook of one section from the loop of the other to effect the hook-off and reversing the operation to effect the hook-on. This practice necessitates presence of an attendant at each well to effect both hook-on and hook-off of the line for that well, and the operation not infrequently results in injury to the attendant through a careless or accidental projection of his hand between the hook and loop.

In accordance with my invention I employ a hook and loop of the general type above described and now commonly employed for manual coupling and uncoupling of the line sections, but provide for effecting either hook-on or hook-off automatically and at a predetermined time through employment of clock mechanism which may be set to release a coupling member at any desired time, together with anchor rod sections 10 and 10' for holding the pump rod section of the main lines in position for recoupling to the power end of the line.

For uncoupling or hook-off of the line I provide the power end 5' of the line with the loop 8, preferably formed rigidly on the end of the line section, and the pump end section 4' with the hook 6 adapted for projection into and removal from the loop to couple or uncouple the sections, and mount the hook-off loop 11 pivotally on the anchor rod line 10' so that it may drop over a second hook 12 on the pump end section 4' of the main line when released by the timing mechanism. For coupling or hook-on of the main line sections I pivotally mount the loop

9 on the end of the pump end section of the main line so that it will drop over the hook 7 on the power end section of the line when released by the timing mechanism; an anchor hook 13 being formed on the pump end section rearwardly of the forward end thereof to receive a loop 14 on the end of the anchor line 10 when the main line sections are uncoupled to hold the pump end section in position for recoupling.

10 Guides, preferably consisting of spaced posts 15-16, are provided for maintaining the rod sections in alignment and the coupling members in superposed relation to insure engagement of one coupling member with the other when a suspended member is released by the timing mechanism.

15 The timing mechanism for releasing the coupling members is the same for either the hook-on or hook-off lines and consists of a post 17 mounted adjacent the coupling position provided with a transverse opening 18 slidably mounting a rod 19 having a pawl 20 pivotally mounted on its outer end to drop when unrestrained, but having a tongue 21 engageable in an aperture 22 in 20 a bracket 23 mounted on the post, and shaped to space the apertured portion thereof from the post.

25 A chain or other flexible connection 24 is adapted for supporting the vertically movable rod coupling member from the latch 20 when the latter is supported in the post bracket but to drop therefrom when the pawl is freed and allowed to drop downwardly on its pivotal mounting under weight of the coupling member. The slide rod 19 is provided at its rear end with a yoke 25 carrying a 30 grooved pulley wheel 26, over which is run a cable or other flexible connection 27, one end of which is connected with a post 28 carried on a lateral arm 29 on the post and the other end with a winding stem 30 of a clock 31, also carried by the lateral arm 29.

35 I preferably employ an alarm clock as the timing mechanism and connect the cable 27 with the stem of the alarm mechanism of the clock in order to effect rapid release of the coupling member when the alarm mechanism of the clock is released.

40 While the lateral arm 29 may be of any suitable construction, I preferably employ a construction including a body member having a pair of curved bands 32 attached to its outer end to house the clock mechanism, and provided with extending ears 33 for mounting the post 28 by bolt and nut connection which serves not only to attach the post to the bands, but to tighten the bands 45 on the clock mechanism.

45 With the form of the invention adapted for automatic hook-off of the line the coupling loop 8 is preferably formed on the end of the power line section and the hook 6 at the extreme end 50 of the pump end section of the rod line, and the anchor line and its pivotal coupling loop arranged above the power line end and its coupling loop.

55 With the parts in this arrangement the anchor line loop is suspended out of the path of travel of the rod line by placing a flexible connector over the pawl 20 and seating the pawl in the opening in the bracket 23, the cable 27 being attached to but unwound from the stem 30 of the 60 alarm mechanism of the clock when the pawl is thus positioned. The clock is then set to release the alarm mechanism and the rod line is reciprocated by the power unit to pump the well continuously through the coupling connection. 65 When the time for which the clock is set arrives

70 the alarm mechanism is released and the cable 7 wound on the stem 30, withdrawing the pawl from its support until it is free therefrom, when weight of the coupling loop on the anchor line drops the loop over the hook 12 on the pump end 75 section of the line as the rod line reaches the forward limit of its stroke. When the rod line moves outwardly the coupling loop 11 is engaged by the hook 12 and holds the pump end section while the power end section continues its forward movement idly.

75 For hook-on as distinguished from hook-off of a line I prefer to mount the vertically movable cable member or loop 9 on the well end section of the rod line so that when the proper time arrives 80 the clock mechanism will effect release of the loop so that it can drop on the hook 7 on the power end section of the line, the well end section being held at the rearward limit of its movement by the anchor loop during idle travel of the 85 power end section.

90 With the rod lines equipped with hook-off and hook-on mechanism, such as I have described, an attendant may at certain hours of the day couple some of the lines and set the timing 95 mechanism therefor to uncouple the lines at certain hours, timing the uncoupling to effect pumping of the respective wells for periods corresponding to known production of the well so that when accumulation in the well has been 100 removed the pumping will be discontinued. He may then set the coupling mechanism of other wells to hook on at certain hours, preferably determined with respect to his next tour of the field, so that those wells which have been automatically hooked on during his absence may be manually hooked off, and the mechanisms of all of the wells of the group reset for repetition of the operations previously described.

105 With such arrangement of the hook-on and hook-off mechanism the active pumping periods may be regulated to avoid pumping after accumulations have been exhausted, and strain on the central pumping unit avoided by stepping of the pumping of different wells so that only one or a 110 limited number of wells may be pumped during any given period, but all of the wells pumped successively between tours of the attendant.

115 What I claim and desire to secure by Letters Patent is:

1. In combination with a rod including power and pump end sections having co-operative coupling members, a hook on the pump end rod section, an anchor having a coupling loop engageable by said hook at the limit of the forward 120 stroke of the pump end rod section, means for releasably retaining one of the coupling members out of coupling position, including a hinged latch pin, a support for the latch pin, a hanger for said coupling member adapted for support on 125 said pin, and clock controlled means for withdrawing said pin from its support to permit the pin to drop and release said hanger.

130 2. In combination with a power line having coupling members and an anchor engageable with one of said members, a support, a latch supporting member carried on the support, a latch carried by said member, a pulley on the latch supporting member, a bracket normally engaging the latch, a flexible member connecting said 135 latch with one of said coupling members to normally support said coupling member from engagement with the other, a clock mechanism carried by the support and having a rotatable shaft, and a flexible cable operating over said pulley and 140

having one end fixed relatively to the support and its other end wound on said shaft to effect release of said latch to cause the supported coupling member to engage with the other coupling member and effect release of the anchor.

5. In combination with a power line having coupling members, a support, a latch releasably connected with the support, a pulley, means connecting the pulley with the latch, a flexible connection connecting the latch with one of said coupling members to support said coupling member out of engagement with the other coupling member, a clock mechanism on the support having a rotating member, and a flexible member 10 operating over said pulley and having one end wound on the rotating member and the other connected to the support for releasing the latch

upon actuation of the rotating member by said clock mechanism.

4. In combination with a power line having pump and power sections, coupling members on said sections, a support, a latch releasably connected with the support, latch carrying means on the support, means connecting the latch with one of said coupling members to support said coupling member out of engagement with the other coupling member, clock mechanism on the support having a rotating member, 15 support having a rotating member, and a flexible member wound on the rotating member and operably connected with the latch carrying means for effecting release of the latch upon actuation of the rotary member by said clock mechanism.
